WELL CASING PIPE

Darrell N. Blake, 143 Glen, Council Bluffs, Iowa 51501

Filed Oct. 11, 1967, Ser. No. 8,960

Term of patent 14 years

Int. Cl. D25—99

U.S. Cl. D23—45

FIGURE 1 is a side elevation of a section of a well casing pipe of this invention.

FIGURE 2 is a sectional view taken along the line 2—2 of FIGURE 1.

FIGURE 3 is a detail of a portion of the casing of FIGURE 1 in the area of one of the perforations.

I claim:

The ornamental design for a well casing pipe, as shown and described.
